CLAIM

The ornamental design for an applicator device for dispensing carbon dioxide enhanced topical substances, as shown and described.

DESCRIPTION

FIG. 1 is a right front perspective view of an applicator device for dispensing carbon dioxide enhanced topical substances in accordance with our new design.

FIG. 2 is a front view of the applicator device for dispensing carbon dioxide enhanced topical substances of FIG. 1.

FIG. 3 is a rear view of the applicator device for dispensing carbon dioxide enhanced topical substances of FIG. 1.

FIG. 4 is a left side view of the applicator device for dispensing carbon dioxide enhanced topical substances of FIG. 1.

FIG. 5 is a right side view of the applicator device for dispensing carbon dioxide enhanced topical substances of FIG. 1.

FIG. 6 is a top view of the applicator device for dispensing carbon dioxide enhanced topical substances of FIG. 1; and, FIG. 7 is a bottom view of the applicator device for dispensing carbon dioxide enhanced topical substances of FIG. 1.

The broken lines depict portions of the applicator device for dispensing carbon dioxide enhanced topical substances that form no part of the claimed design. The shade lines shown through the views are to indicate surface contour and are not intended to be surface ornamentation.

1 Claim, 7 Drawing Sheets
